US00D774069S

(12) **United States Design Patent** (10) Patent No.: **US D774,069 S**
(45) Date of Patent: **** Dec. 13, 2016**

(54) **DISPLAY SCREEN WITH GRAPHICAL USER INTERFACE**

(71) Applicant: **Microsoft Corporation**, Redmond, WA (US)

(72) Inventors: **David Gardner**, Covington, WA (US); **Eric Hsia**, Seattle, WA (US); **MacBeth Watson**, Redmond, WA (US); **Brian Ralphs**, Seattle, WA (US); **John Snavely**, Seattle, WA (US); **Megan McMillan**, Seattle, WA (US)

(73) Assignee: **Microsoft Corporation**, Redmond, WA (US)

(**) Term: **15 Years**

(21) Appl. No.: **29/530,094**

(22) Filed: **Jun. 12, 2015**

(51) LOC (10) Cl. **14-04**

(52) U.S. Cl.

USPC **D14/486**

(58) **Field of Classification Search**

USPC **D14/485-495**

See application file for complete search history.

(57) **CLAIM**

The ornamental design for a display screen with graphical user interface, as shown and described.

DESCRIPTION

The FIGURE is a front view of a display screen with graphical user interface showing our new design.

The broken line showing of the remainder of the user interface and the remainder of the display screen is for environmental purposes only and forms no part of the claimed design.

1 Claim, 1 Drawing Sheet
